UNITED STATES PATENT OFFICE

2,435,172

STACK FOR FURNACES

William George Young, Chicago, Ill., assignor to
 Chicago Fire Brick Company, a corporation of
 Illinois

Application March 31, 1945, Serial No. 585,903

12 Claims. (Cl. 72—93)

1

My invention relates to smoke stacks and more particularly to a stack for furnaces.

It is the purpose of my invention to provide a smoke stack in which cumbersome weight is eliminated by avoiding cumulative load, thus requiring less foundation and providing a thin wall section by using supporting means having much greater strength per unit of weight than the refractory tile and the bricks usually employed for smoke stacks. The supporting means has adequate tensile strength as well as load bearing capacity and the brick and tile of the stack cooperate to give adequate stability against tipping of the stack.

In view of the fact that high temperatures are encountered in stacks of the character in which my invention is applied, it is necessary that suitable means be provided for cooling the stack, particularly the metallic framework, in order that the life thereof, and of the stack itself, be greatly lengthened. Furthermore, due to the cooling of the stack, the refractory material used in the stack is given a long life as compared with a stack that is not so cooled.

More particularly, my invention comprises a smoke stack that has a structural frame made up of metallic members, which supports spaced inner and outer walls to provide an air space between said walls from substantially the bottom to substantially the top of the stack, said space providing an air passage extending throughout substantially the height of the stack. Means is provided for creating a current or draft of cooling air substantially vertically of the stack through said passage, this being accomplished by providing air inlet openings leading from the outside air or atmosphere into said air chamber or space near the bottom thereof, and air outlet or discharge openings leading to the outer air near the top of the stack from said air passage.

Another feature of my invention is that any section of the inner refractory lining can be independently removed without affecting any of the others, as each section is independently supported on the framework. Inasmuch as there would ordinarily be a difference in the coefficient of expansion of the wall members and the metallic framework, means is provided to allow for expansion and contraction, thus avoiding any possibility of distortion of the wall of the stack.

Furthermore, due to the character of structure used in the stack, high wind velocity is easily withstood because of the fact that the framework is sturdy and thoroughly supports the entire wall structure. Also, the erection of a stack made in

2

accordance with my invention is simpler than that of a stack which is supported from the bottom thereof, resulting in a cumulative load as the height of the stack increases.

- 5 Another advantage of a stack made in accordance with my invention is that it will withstand disaster, such as windstorm or earthquake damage, much better than a stack that is not made in accordance with the principles of my invention.
- 10 An important feature of the invention is that while the metallic framework and outer wall are cooled, the inner wall providing the smoke passage is maintained at substantially a uniform temperature throughout its height, by insulating said
- 15 wall from the air passage. This will increase the draft in the stack, while reducing maintenance expense. As each section of the stack is independent of all other sections thereof, any maintenance required will be reduced in cost.
- 20 Other objects and advantages of my invention will appear as a description of the drawing proceeds. I desire to have it understood, however, that I do not intend to limit myself to the particular details shown and described except as
- 25 defined in the claims.

In the drawings—

Fig. 1 is a vertical elevational view of my improved stack, partly broken away;

Fig. 2 is a section taken on the line 2—2 of

30 Fig. 1 on a somewhat larger scale than Fig. 1;

Fig. 3 is a fragmentary elevational view of the

framework as viewed from the inside thereof;

Fig. 4 is a fragmentary sectional view on sub-

stantially the same scale as Fig. 2, taken on the

35 line 4—4 of Fig. 1;

Fig. 5 is a fragmentary perspective view of a

portion of the framework and a portion of the

inner sectional wall structure;

Fig. 6 is a vertical sectional view through the

40 stack, partly broken away;

Fig. 7 is a fragmentary vertical sectional view

on a somewhat larger scale than Fig. 6 of the up-

45 per end portion of the stack;

Fig. 8 is a similar view to Fig. 7 of the lower

end portion of the stack;

Fig. 9 is a fragmentary vertical sectional view

through the stack at an offset in one of the ver-

tical frame members;

Fig. 10 is a perspective view of a supporting

50 bracket for the inner refractory wall members;

Fig. 11 is a similar view of an anchor casting

for said inner wall members;

Fig. 12 is a perspective view of one of the inner

refractory wall members;

Fig. 13 is a perspective view of one form of tile

or block that can be used in the outer wall of the stack; and

Fig. 14 is a fragmentary sectional view on substantially the same line as Fig. 6 but showing a slightly different construction.

Referring in detail to the drawings, my improved smoke stack is mounted on a suitable foundation 20, which is shown as being made of concrete, which may be suitably reinforced as may be found necessary. Mounted on plate members 21 on said foundation are vertical frame members or columns 22 which are preferably of an H cross section. It will be noted upon reference to Figs. 1 and 2 that the particular stack illustrated is polygonal in cross section, being shown as being hexagonal, although my invention can be applied to a circular stack or one of any other desired cross sectional shape. The columns 22 are located at the corners of the polygonal structure shown in Figs. 1 and 2 and are provided with inner and outer flanges 23 and 24, respectively, the flanges 23 being exposed on the outer face of the stack.

Secured in any suitable manner at regularly spaced intervals on said columns 22, as by means of the brackets 25, are the transverse horizontally extending channel members 26 upon which the sections of the outer wall structure are supported. The outer wall structure may be made of tile or ordinary brick or of any other suitable material that can be sectionally mounted on said channel members 26, said wall sections being indicated generally by the numeral 27 in the drawings. Upon reference to Fig. 1, it will be noted that the columns of the framework are gradually reduced in size in view of the decreasing load thereon from bottom to top of the stack. In Fig. 9, the joint structure between a lower heavier column and an upper lighter column is shown. Platelike members 28 and 29 are provided for connecting the flanges of the upper and lower column members at such a joint, a filler member 30 being provided between the platelike member 29 and the flange 23 of the smaller of the two column members on the outer side of the stack to provide a rigid joint at the offset thus provided in the outer wall of the stack. Angle brackets 31 and 32 connect the column members and the web portion 33 of one of the channel members 26 at such a joint in order to thoroughly brace the structure in all directions and to, at the same time, mount one of said transverse channel members 26 of the framework in position.

The flanges 24 of the columns 22 have brackets 34 fixed thereto at regularly spaced intervals by welding or otherwise, said brackets having obliquely extending end portions 35 having apertures 36 for securing the transverse inner frame members 37 thereto by means of bolts 38 or similar securing members. The transverse members 37 constitute the horizontal supporting members for the sections of the inner wall of the stack and may be castings, each of said members 37 being provided with a series of longitudinally extending aligned slots 39 and with laterally extending longitudinal ribs 40, 41, 42 and 43; the ribs 40 and 42, and the ribs 41 and 43, lying opposite each other in the form of the invention shown.

Mounted between the horizontal supporting members 37 are vertically extending retainer members 44, said retainer members having a web portion 45 and flanges 46 and 47 thereon. The flanges 46 and 47 extend beyond the web portion 45 at the ends of the retainer members

5 to provide ears 48 and 49 on the opposite ends of said retainer members, a transverse flange 50 being also provided at the end of each web portion 45, thus providing a seat at each end of each retainer member 44 that receives the bottom and top edges of the horizontal supporting members between which said retainer members are mounted. The flanges 47 are provided with cut-away portions or notches 51 therein to provide a reduced portion in each of said flanges 47 for a purpose to be described below.

10 Suitable spacing blocks 52 are provided between the retainer members 44 and the obliquely extending ends 35 of the brackets 34 so as to properly space the horizontal supporting members 37 from the flanges 24 of the columns 22. The framework of the stack is preferably provided with suitable bracing means comprising the diagonally extending members 53 secured to the 15 channel members 26. While a certain type of bracing is shown in Fig. 3 of the drawings, obviously this can be varied as may be found desirable.

20 Adjustably mounted in the slots 39 of the horizontal supporting members 37 are supporting brackets 54, one of said brackets being shown in detail in Fig. 10. Each of said brackets has a flat shelf portion 55 terminating in an upturned flange or lip 56. Each of said supporting brackets 25 is provided with a reduced portion 57 and has a shoulder at 58 which engages with the rib 40 on the horizontal supporting member 37 so as to seat thereon. Said bracket further comprises a 25 vertically extending portion 59 extending from the shoulder 58 and terminates in a flanged horizontally extending portion 60 providing a head 61 thereon, said head being greater in vertical than horizontal extent so that the same will pass through the slot 39 by turning the same to a position substantially at ninety degrees to that shown in Fig. 5, whereby the head portion 61 may be inserted through the slot and, after being turned to the position shown in Fig. 5, will be mounted in position so that it will be prevented from disengagement from the horizontal retaining member 37. The supporting bracket is further provided with a rounded corner at 62 and suitably braced by means of the web portion 63. Said bracket 54 is preferably cast of a suitable alloy capable of withstanding the temperatures to which it will be subjected in the stack. It is, of course, to be understood that one of said brackets 54 is mounted in each of the slots 39, certain of said brackets being omitted from Fig. 5 for the sake of clearness.

25 Mounted on the vertical retaining members 44 are anchor brackets 64. Said anchor members are also preferably cast of similar material to the members 54 and are provided with a plurality of prongs or ears 65 which terminate in vertically extending lugs 66, said lugs extending upwardly and downwardly beyond the body portion of the member 64. Said anchor members are further provided with flanges 67 at the opposite end thereof to the prongs 65 and a slot 68 is provided between said flanges 67 which is wide enough so that the anchor casting may be passed through the notches or openings 51 at the reduced portion in the retainer member 44 to thus assemble said anchor casting 64 with said retaining member 44, the anchor casting being provided with an opening 69 therein which has an offset 70 to accommodate the flange 47 on the vertical retainer member 44 with which the same is associated. 30 Said anchor members 64 are thus slidably con-

nected with the retainer members 44 but interlock therewith so as to prevent any movement of the same except longitudinally of the members 44.

The inner wall is preferably made of tiles or blocks of refractory material 71, one of which is shown in in perspective in Fig. 12. Said blocks 71 are preferably shouldered to provide extensions 72 and 73 on the opposite ends of said blocks that are adapted to overlap when said blocks or refractory tiles are in position in the stack. Said refractory members 71 are further provided with longitudinally extending grooves 74 in the upper and lower faces thereof.

In assembling one of the inner wall sections, the bottommost row of tiles or refractory members 71 is first placed in position on the brackets 54, the upwardly extending lips or flanges 56 being seated in the groove 74. It will be noted, however, upon reference to Figs. 5, 7 and 8, that the upstanding lip or flange 56 does not extend to the bottom of the groove 74, but that the bottom face of the tile 71 rests on the platform 55. The spacing of the horizontal supporting members 37, and thus of the shelflike portions 55, is such relative to the vertical dimensions of the tiles 71 that a slight space will exist between the top faces of the uppermost tiles 71 of one inner wall section and the bottom faces of the bottommost tiles 71 of the next higher wall section mounted on said brackets 54, which is filled with a refractory cement as indicated at 75, said cement extending into the groove 74 running along the top of the tiles 71 of the lower section at this point. This provides an expansion joint inasmuch as the shelflike portions 55 of the brackets are spaced from the uppermost tiles of the lower wall section and the top edges of the flanges or lips 56 are spaced from the bottoms of the grooves 74 in the bottommost tiles of the upper wall section, as will be obvious from Figs. 7 and 8.

After the lower row of refractory tiles 71 has been placed in position, anchor castings 64 are assembled with the vertical retainer members 44 with the downwardly extending portions of the lugs 66 thereon mounted in the grooves 74 in the top faces of the tiles 71, and after all said brackets have been thus assembled with the bottom row of tiles of said wall section, the next row of tiles is placed in position with the groove 74 in the lower faces thereof receiving the upwardly extending portions of the lugs 66 of the anchor castings 64. This is continued with the anchor castings and tiles until the desired height of wall section is built up, reaching to the next higher horizontally extending supporting member 37, whereupon the same procedure is followed with the succeeding wall section. It will be obvious that with the arrangement of supporting and anchoring members thus provided, any uneven expansion of the parts of the wall will be taken care of by the connections between the various metallic parts and the connections between said metallic parts and the refractory wall made up of the tiles or blocks 71.

It will be noted that the inner wall made up of the refractory members 71 is mounted in spaced relation to the outer wall made up of the sections 27 to thus provide a space 76 that runs from the foundation 20 to the cap tiles 77 provided on the stack. The space 76 provides a vertically extending air shaft or cooling conduit extending substantially from the bottom to the top of the stack, and means is provided for circulating air therethrough by creating an up-

draft through the space 76, air inlet openings 78 at suitable points near the bottom of the stack being provided in the outer wall, and air outlet or discharge openings 79 being provided adjacent the top end of the outer wall, said air inlet and outlet openings leading respectively from the outside air or atmosphere to the space or chamber 76, and from said space or chamber to the outside air or atmosphere. Preferably, suitable frame members 80 and 81 define the openings 78 and 79. The spacing and number of the openings 78 and 79 may be varied as desired and as may be found necessary to get the desired quantity of air flow through the cooling passage provided by the space 76. It will be noted that substantially all of the metallic members either lie within or extend into the space 76 and being all of heat conducting material, said members will thus all be cooled by the air flowing through the passage 76 and will not reach a temperature, no matter how high the temperature of the products of combustion passing through the stack may be, that will be harmful to any of the metallic parts of the frame or the supporting and retaining means of the refractory members or tiles 71 forming the inner wall of the stack.

The bottommost section 27 of the outer wall may be mounted directly on the foundation 20 or on the platelike member 21, and an angle 30 member 82 is provided for securing the columns to said platelike member and to properly align the bottommost wall sections. Additional angle brackets 83 may be provided for securing said columns to said bottom plates 21. The outer wall 35 may be made, if desired, of the tiles shown in Fig. 13, which are merely rectangular block-like members 84 having openings 85 therein and a web portion 86 between said openings 85. Said outer wall is also provided with an access opening 40 which is indicated at 87, provided with walls 88 that separate this opening from the space 76, a door 89 being provided leading to the access opening 87, said door being mounted in a suitable frame 90. Similarly, a breech opening may 45 be provided which is also separated from the chamber 76 and to which access is had through a door 91 mounted in a suitable frame 92.

At the upper end of the stack, the outer wall is preferably provided with a stepped portion 93 50 on which an inverted channel member 94 is mounted which supports the cap blocks 77 which are mounted on the I-beam 95 secured to the channel member 94 so as to prevent any lateral shifting of said blocks.

The uppermost inner wall section is mounted in a somewhat different manner than the other wall sections, due to the fact that the vertical retainer members 44 are omitted. The tiles 71' of said uppermost wall section are provided with grooves 74' in the vertical faces thereof, which receive lugs or ears 96 on the tie-back brackets 97. The brackets 54 are provided on the horizontal supporting member 37 at the bottom of said uppermost inner wall section and cooperate with grooves in the bottom faces of said tiles 71' in the same manner as previously described. The brackets 97 are, however, also mounted on said uppermost members 37, having spaced design flanges 98 and 99 defining a groove in which the top edge of the member 37 seats to thus hold said member 97 in position on the member 37. The uppermost wall section is only made up of one row of the refractory members 71', as shown in the drawings. The cap members 77 are, of course, mounted on said members 71' as well as

on the members 94 at the top of the outer wall of said stack.

An insulating lining 100 is provided on the outer face of the inner wall made up of the refractory members 71, which not only aids in cooling the metal framework but also keeps the inner wall uniformly hot throughout its height, increasing the draft in the stack, said lining is made up of solid blocks or sheets extending from one member 64 to the next adjacent one.

In Fig. 14 of the drawings I show a slight modification wherein the outer wall is made of large sections 101 of sheet material. Any suitable weather resisting material whether metallic or non-metallic may be used. It provides a much lighter construction.

A smoke stack is thus provided which is made up of a metallic framework upon which outer wall sections and inner wall sections are independently mounted and an air space or chamber is provided between said inner and outer walls of the stack, to which all of the metallic parts are exposed and in which a continuous flow of cooling air exists to continuously cool the metallic parts of the stack, thus preventing any damage to any of the frame portions or supporting means for the inner refractory wall, due to the heat existing in the smoke passage of the stack which is transferred to the refractory blocks 71.

Having thus described my invention, what I claim as new and desire to secure by Letters Patent is:

1. A stack of the character described, comprising a framework and inner and outer walls supported by said framework, said walls being spaced to provide a passage therebetween, said framework lying principally within said passage.

2. A stack of the character described, comprising a framework and inner and outer walls supported by said framework, said walls being spaced substantially from bottom to top thereof to provide a vertical air passage in said stack, said stack being provided with inlet means for admitting air from externally of said stack thereto adjacent the bottom thereof and with outlet means for discharging air therefrom adjacent the top thereof, and being fluid tight between said inlet and outlet means.

3. A stack of the character described, comprising a framework and inner and outer walls on opposite sides of and supported by said framework, said stack being provided with means for cooling said framework.

4. A stack of the character described, comprising a framework and inner and outer walls on opposite sides of and supported by said framework, said walls being spaced to provide a passage therebetween containing the major portion of said framework and said stack being provided with means for circulating a cooling medium in said passage in contact with said framework.

5. A stack comprising a metallic framework, an inner imperforate refractory wall supported by said framework and providing a barrier between said framework and the passage for the products of combustion in said stack, and an outer wall spaced therefrom, said framework being confined within and between said walls and said stack being provided with means for admitting air at atmospheric temperature to the space between said walls and discharging heated air therefrom.

6. A stack of the character described, comprising a framework and inner and outer walls sectionally supported by said framework, said walls being spaced to provide a passage therebetween, and said framework lying within the outer periphery of said outer wall and having portions extending into said passage.

7. A stack polygonal in cross section having vertically extending frame members at the corners thereof, an outer wall having sections mounted between and supported by said vertical frame members, transverse frame members on the inner sides of said vertical frame members and an inner wall of refractory material mounted inwardly of said transverse frame members and supported thereby, said walls defining an air space which said vertical and transverse frame members traverse.

8. A stack of the character described, comprising a framework and inner and outer walls sectionally supported by said framework, said walls being spaced to provide a passage therebetween, said stack being provided with expansion joints between the sections of said inner wall.

9. A stack of the character described, comprising a framework and inner and outer walls supported by and confining said framework, said stack being provided with means for cooling said framework, and means for insulating said inner wall from said cooling means.

10. A stack comprising a metallic framework, an inner refractory wall supported by said framework and providing a barrier between said framework and the passage for the products of combustion in said stack, insulation on the outer face of said refractory wall, and an outer wall spaced therefrom, the major portion of said framework being exposed to said passage and lying outwardly of said insulation said stack being provided with means for admitting air at atmospheric temperature to the space between said walls and discharging heated air therefrom.

11. A stack of the character described, comprising a framework and inner and outer walls supported by said framework, said walls being spaced to provide a passage therebetween, said framework lying principally within said passage, and a cap closing the upper end of said passage supported by said framework.

12. A stack of the character described, comprising a framework and inner and outer walls supported by said framework, said walls being spaced to provide a passage therebetween, said framework lying principally within said passage, and comprising vertical frame members mounted in said outer wall and projecting into said passage, and supporting means for said inner wall carried by said vertical frame members and mounted in said passage.

WILLIAM GEORGE YOUNG.
